(57) **CLAIM**

The ornamental design for a plant sensor system, as shown and described.

DESCRIPTION

FIG. 1 Is an environmental view of the claimed design.

FIG. 2 Is a perspective view of the claimed design of FIG. 1.

FIG. 3 Is a front planar view of the claimed design of FIG. 1.

FIG. 4 Is a back planar view of the claimed design of FIG. 1.

FIG. 5 Is a left side planar view of the claimed design of FIG. 1.

FIG. 6 Is a right side planar view of the claimed design of FIG. 1.

FIG. 7 Is a top planar view of the claimed design of FIG. 1.

FIG. 8 Is a bottom planar view of the claimed design of FIG. 1.

FIG. 9 Is an environmental view of the claimed design.

FIG. 10 Is a perspective view of the claimed design of FIG. 9.

FIG. 11 Is a front planar view of the claimed design of FIG. 9.

FIG. 12 Is a back planar view of the claimed design of FIG. 9.

FIG. 13 Is a left side planar view of the claimed design of FIG. 9.

FIG. 14 Is a right side planar view of the claimed design of FIG. 9.

FIG. 15 Is a top planar view of the claimed design of FIG. 9; and,

FIG. 16 Is a bottom planar view of the claimed design of FIG. 9.

The broken-line disclosure shown in the views is understood to represent portions of the article in which the claimed design is embodied, but which form no part of the claimed design.

The text “plantlink” in FIG. 8 is a registered trademark and forms part of the claimed design, according to a first
